UNITED STATES PATENT OFFICE

2,632,961

DRIER

Alexander Robertson, Philadelphia, Pa., assignor
to Venango Engineering Co., Inc., Philadelphia,
Pa., a corporation of Pennsylvania

Application October 25, 1951, Serial No. 253,140

10 Claims. (Cl. 34—162)

1

This invention relates to garment dryers. More particularly, it relates to garment-drying apparatus for articles which have been bleached, dyed and washed or similarly treated. The invention is useful for drying articles of various sorts but finds particular utility in drying hosiery.

It is an object of the invention to provide economical and simple garment-drying apparatus of less length than heretofore yet affording full time for drying without sacrifice of quality and durability.

Another object is to provide in an apparatus of the foregoing type means particularly for drying those parts of the garment which are last or most difficult to dry.

Other objects and advantages of my invention will appear as it is described in connection with the accompanying drawings.

In the drawings:

Fig. 1 is a side elevation view partly in section of the invention;

Fig. 2 is an end elevation view partly broken away of the entrance end of the invention shown in Fig. 1;

Fig. 3 is a fragmentary vertical section view taken along line 3—3 of Fig. 1;

Fig. 4 is a fragmentary detail view in perspective of one side of a tray as used in Figs. 1—3;

Fig. 5 is a transverse vertical section view taken along line 5—5 of Fig. 1;

Figs. 6 and 7 are views similar to Fig. 1 but of two other forms of the invention.

Referring to the drawings, the dryer D in Figs. 1—5 is enclosed within a rectangular housing having vertical parallel side walls 10, 12 and end walls 13, 14. Rising in extension of the side walls 10, 12 at their mid-portions are parallel walls 15, 17 joined by vertical parallel end walls 16 and 18 forming a rectangular tower covered by a top wall 19. Preferably the tower walls are insulated to minimize heat loss by having sheets of heat insulating material 20 attached in any suitable conventional fashion to the inside surface of the vertical and top walls.

To provide heat within the housing, an electric heating unit is located just below the top of the tower. The unit is comprised of a series of interconnected electrically resistant rod or wires 22. The invention is not limited to such heating means however since other suitable heating means may be employed.

Circulation of air or other drying medium through the housing is effected by means of a fan 24a mounted in a rectangular box-like cupola 24 above an opening in the top wall of the housing. Air is drawn in through an inlet opening 23 in

2

the cupola, forced downwardly through the housing by the fan 24a and exhausted therefrom through an outlet opening 64 in the lower portion of the housing. A conduit 21 positioned exteriorly of the dryer housing interconnects the inlet and outlet openings 23 and 64, respectively, to permit recirculation of any desired portion of the air. A pair of adjustable dampers 21a and 21b are provided in the conduit 21 to permit the desired quantity of fresh air to be drawn into the housing.

For conveying articles through the heated housing, a moving conveyor is provided comprising two spaced parallel link chains 30, 32 which move in planes parallel to the side walls of the housing. These chains pass around rotating power-driven sprocket wheels 31 at opposite ends of a shaft 34 transversely mounted at one end of the housing in bearings in the opposite side walls of the housing. Similar sprockets 35 are on a similar shaft 36 similarly mounted at the opposite end of the housing.

To carry the conveyor chains up into the tower, each chain passes around a sprocket 38 on a stub shaft 39. These two shafts 39 are aligned and are located at the lower corners of the tower and are journaled in bearings in the side walls of the tower. From sprockets 38, the chains run vertically to and around sprockets 42 on stub shafts 43 in bearings 44 within the side walls of the tower in the neighborhood of the heating unit, all similarly to the sprockets 38. The chain then runs horizontally under and parallel to the heating unit to other similarly mounted sprockets 46 and then down to and around sprockets 48 like and mounted similarly to sprocket 38 but in opposite lower corners of the tower. The chains then run horizontally to and around sprockets 35.

To support the chains between sprockets 31 and 35, they pass over sprockets 49 on stub shafts 49 in the side walls of the housing.

For supporting and carrying the articles to be dried, trays are pivotally suspended at spaced points along and between the chains. Each tray may comprise a platform 50 of wire mesh or screen or other latticed or perforated material through which air can circulate. A rectangular frame 52 around the mesh 50 has triangular supporting plates 54 attached to and extending perpendicularly upward at its ends with a laterally-extending hollow bearing member 56 affixed to the apex of each plate to loosely receive pins 58 extending laterally inward from the chains at spaced points. Gravity will hold the trays with their platforms horizontal as the conveyor moves 55 around its path, whether the movement be ver-

tically up into or down from the tower or horizontally. The use of stud shafts to mount the sprocket wheels leaves the space free between the chains in which the trays can move. Although sprockets 31 and 35 are larger and are on shafts extending fully across the housing, they could be mounted on stud shafts if desired, or in case the sprockets radii were less than one-half the width of the trays.

As the conveyor moves in the direction of the arrow *d*, an attendant may lay articles to be dried on the trays through the open upper face of the lower level of the housing as at *E*. The articles can be removed in the same way, if dry, by another attendant at the opposite end of the housing as at *X*, or they may be allowed to return on the trays to their starting point and removed simultaneously with the placing of new articles to be dried on the tray.

To prevent entanglement of articles with the conveyor chains, flanges 59 may be bent down from the housing around the chains and adjacent the deposit and removal openings *E* and *X*.

When hosiery is to be dried, it is desirable that the hottest, driest incoming air be directed toward the feet and top welts which are more difficult or slower to dry than the legs. For that purpose, a baffle 60 is placed in the top of the tower beneath the heating unit and between it and the path of the trays passing beneath. The baffle may be a metallic plate having a central peak 61, running parallel to the path of the conveyor, toward which the plate rises from its sides. The baffle may extend completely across the tower in the direction of travel of the conveyor and be supported from the tower walls. The sides of the baffle terminate short of the tray length so that air will be forced down through the trays at their ends where the tops and bottoms of the stockings are.

To tend to confine the circulation mainly in the tower, an inwardly inclined insulated floor or bottom baffle 62 may be provided between the upper and lower runs of the chains, and an exhaust port 64 may be provided in the side wall of the housing just above the floor. Confining the circulation within the tower permits closer temperature control, which is particularly desirable in drying textiles susceptible to temperature variation; also greater economy of power is thereby achieved.

In Fig. 6 a modified form of dryer *D1* is shown like the form of Figs. 1-5 except that four additional vertical passes within the tower are provided. That is done by providing an additional pair of sprocket wheels 71 at the top and two additional pairs of sprocket wheels 70, 72 at the bottom of the tower. The chains from the first pair of sprocket wheels 42 (as in Figs. 1-5) runs down and around the additional lower pair 70 and up and around the additional upper pair 71; and then down and around the second lower pair 72 and up and around the upper pair 46 (as in Figs. 1-5). This arrangement allows further decrease in length in the dryer without adding more to its height or materially increasing the cost.

In Fig. 7 a third form of dryer *D2* is shown differing from Figs. 1-5 in elimination of two pairs of sprockets and also of the ability to remove the dried articles from the far end of the dryer, i. e. opposite that in which they enter. The far end of the machine is shortened up to the tower wall, the sprocket 35 is eliminated and the sprocket 40 is placed lower as at 75. The sprocket pair 48 is or may be omitted. It is

necessary to lay the articles to be dried on the trays at *E* as before and to take them off on their return to *E*.

Other modifications within the scope of my invention will occur to those skilled in the art.

I claim:

1. Garment drying apparatus comprising a housing having a horizontally extending section and a tower section, a conveyor within said housing having a horizontal run within said horizontal section, and vertical runs within said tower section, garment carrying trays, means to pivotally support said trays at spaced points along said conveyor, said trays having a perforated garment supporting platform portion maintained horizontally by gravity throughout the entire path of travel of said conveyor, means to introduce air for drying garments on said trays, means to deflect the incoming air toward the ends of said trays at the top of the tower, and means adjacent the bottom of the tower substantially confining the circulation of drying air to said tower but permitting entrance and exit of said conveyor.

2. Garment drying apparatus comprising a housing having a horizontally extending section and a tower section, a conveyor within said housing having a horizontal run within said horizontal section, and vertical runs within said tower section, garment carrying means pivotally supported from said conveyor at spaced points therealong, said garment carrying means having a horizontal garment supporting portion maintained horizontal by gravity throughout the entire path of travel of the conveyor, means introducing air for drying the garments on said carrying means, and means to deflect incoming air toward the ends of said carrying means.

3. Garment drying apparatus comprising a housing having a horizontally extending section and a tower section, a conveyor within said housing having a horizontal run within said horizontal section, and vertical runs within said tower section, garment carrying means suspended from said conveyor at spaced points therealong, said garment carrying means having a garment supporting portion maintained in garment-supporting position by gravity throughout the entire path of travel of the conveyor, means introducing air for drying the garments on said carrying means, and means to deflect incoming air toward the ends of said carrying means.

4. Garment drying apparatus comprising a housing having a horizontally extending section and a tower section, a conveyor within said housing having a horizontal run within said horizontal section, and vertical runs within said tower section, garment carrying means pivotally suspended from said conveyor at spaced points therealong, said garment carrying means having a garment supporting portion maintained in garment-supporting position by gravity throughout the entire path of travel of the conveyor, means introducing air for drying the garments on said carrying means, and means to deflect incoming air toward the ends of said carrying means, and means adjacent the bottom of the tower substantially confining the circulation of drying air to said tower but permitting entrance and exit of said conveyor.

5. A garment dryer as claimed in claim 4 having means to exhaust air from said tower located adjacent the tower bottom.

6. A garment dryer as claimed in claim 3 having a second horizontally extending portion, said first and second horizontal portions having open-

ings in their top surfaces to permit deposit of garments on said conveyor through one opening and removal through the other opening.

7. A garment dryer as claimed in claim 3 having means causing said conveyor to run horizontally adjacent the top of the tower, said deflecting means being between the top of the tower and said tower-top run of the conveyor.

8. A garment dryer as claimed in claim 3 having a heating unit adjacent the top of the tower, said deflecting means being between said unit and the path of the conveyor in the upper part of the tower causing the incoming air to be heated during its deflection to the ends of the carrying means.

9. A garment dryer as claimed in claim 2 having a heating unit adjacent the top of the tower, said deflecting means being between said unit

and the path of the conveyor in the upper part of the tower causing the incoming air to be heated during its deflection to the ends of the carrying means.

10. A garment dryer as claimed in claim 3, having means causing said conveyor to make a series of vertical runs in said tower.
